UNITED STATES PATENT OFFICE

137,790

DESIGN FOR A TOY BANK

James Lewis Darling, Philadelphia, Pa., assignor of one-half to John Milton Davis, Blue Ridge Summit, Pa.

Application November 4, 1943, Serial No. 111,586

Term of patent 3½ years

(Cl. D34—11)

To all whom it may concern:

Be it known that I, James Lewis Darling, a citizen of the United States, residing at Philadelphia, in the county of Philadelphia and State of Pennsylvania, have invented a new, original, and ornamental Design for a Toy Bank, of which the following is a specification, reference being had to the accompanying drawing, forming part thereof.

I claim:

The ornamental design for a toy bank, as shown.

JAMES LEWIS DARLING.
